A. W. EMERSON

ADJUSTABLE SCREEN

Filed Oct. 6, 1922

UNITED STATES PATENT OFFICE.

ALFRED W. EMERSON, OF STEUBEN, MAINE, ASSIGNOR OF ONE-HALF TO BARTLETT W. BROWN, OF MILBRIDGE, MAINE.

ADJUSTABLE SCREEN.

Application filed October 6, 1922. Serial No. 592,772.

To all whom it may concern:

Be it known that I, ALFRED W. EMERSON, a citizen of the United States, residing at Steuben, in the county of Washington, State 5 of Maine, have invented certain new and useful Improvements in Adjustable Screens; and I do hereby declare the following to be a full, clear, and exact description of the invention, such as will enable others skilled in 10 the art to which it appertains to make and use the same.

This invention relates to new and useful improvements in screens and particularly to window screens.

15 One object of the invention is to provide a window screen which is adjustable transversely of the window, and which affords no opening through which insects may pass, as is the case with the ordinary two section adjustable screens now on the market.

Another object is to provide an adjustable screen of this character which is capable of being easily and quickly adjusted to fit windows of different widths, and which 25 can be easily and quickly collapsed to its minimum width, without injury to the screen fabric.

Other objects and advantages will be apparent from the following description when 30 taken in connection with the accompanying drawing.

In the drawing:

Figure 1 is an elevation of the screen as viewed from one side and in collapsed position.

Figure 2 is an elevation as viewed from the opposite side, the screen being extended, and partly broken.

Figure 3 is an enlarged transverse sectional view on the line 3—3 of Figure 2.

Figure 4 is a longitudinal sectional view on the line 4—4 of Figure 2.

Referring particularly to the accompanying drawing A and B represent the two sliding frame sections of the screen, which include, respectively, the longitudinal side bars 10 and 10' and the outer transverse connecting bar 11 and 11'. Secured to the frame section A is a strip of screen wire fabric 12, one end of which extends to a considerable distance beyond the open end of the frame, for a purpose which will presently appear herein. The longitudinal edges of the screen fabric are held in place on the frame section

A, by means of the batten strips 13, the same 55 extending outwardly from the faces of the side bars 10 to serve as guides and guards for the strips or bars 10' of the section B. Secured to the outer edge faces of the side bars 10, of the section A, are the metal strips 60 14, the same having their outer edges projecting beyond the faces of the bars 10, in parallel relation to the battens 13, to form the outer guides for the bars 10' of the section B. Secured to the outer end portions of 65 the battens 13, and to the bars 10 of the section A, are the retaining straps 15, which maintain the bars 10' of the section B within the confines of the strips 14 and the battens 13, as the sections A and B are moved 70 longitudinally with respect to each other. On the other wider faces of the bars 10' of the section B which are longitudinally rabbed, as seen at 12' there are secured the longitudinally extending metal plates 16, between which and the adjacent wider faces 75 of the bars 10', the portions of the longer marginal edges of the screen fabric, beyond the open end of the frame section A, slide.

Mounted on the end portions of the wider 80 face of the transverse bar 11', of the section B, opposite the adjacent ends of the metal plates 16, are the outstanding apertured brackets 17 in which are rotatably supported the ends of the roller 18. Secured to this 85 roller is the shorter marginal edge of the outer end of the screen fabric 12, and on this roller the said projecting portion of the screen fabric is arranged to be rolled. Curved housings 19 are secured to the brackets 90 17, to cover the adjacent ends of the roller 18. It will be noted that the outer ends of the metal plates 16 are disposed close to the ends of the cross bar 11' of the section B, so that as the screen fabric passes 95 from beneath the ends of the metal plates, there will be no gap or opening, through which insects might find passage.

Secured to each end of the roller 18, and wound thereon, in the same direction, is the 100 end of a cord 20, the same passing through an opening 21, in the adjacent end of the side bar 10, and around a grooved roller 22, mounted in said opening, and thence longitudinally of the bar 10', within a groove 23, to a point adjacent the other end of the bar 10', where it passes around a grooved roller 24 mounted in an opening 25, in the 105

said bar, and is secured within a kerf 26, formed in the adjacent end of the side bar 10 of the frame section A.

From the foregoing it will be seen that 5 when the sections A and B are pulled apart, or away from each other, the strain of the screen fabric will exert pull on the roller, causing the same to rotate and unwind the screen fabric. At the same time the cords 10 will run over the pulleys or rollers, so as to pay out. When the sections are pushed together, the pull of the ends of the cords, due to the force exerted thereagainst by the ends of the bars 10 of the section A, will cause 15 the other ends of the cords to turn the roller 18 in the opposite direction, with the result that the said cord ends will be unwound from the roller and the screen fabric wound thereon.

20 By this construction the screen is capable of adjustment to any degree without permitting any opening for insects, the fabric being continuous from end to end.

What is claimed is:

25 1. An adjustable window screen comprising a pair of slideable sections, a screen carrying roller on one of the sections, the side rails of the roller section having openings adjacent their ends, rollers mounted in the 30 openings, and a cord connected to the outer end of each of the side rails of the other

section and to one end of the screen carrying roller and engaged around the said rollers within the respective openings of the corresponding rail of the roller carrying section. 25

2. An adjustable window screen comprising a pair of slideable sections having engaged side rails, the rails of one section being channeled to receive the rails of the 40 other section, the rails of the other section having openings adjacent the opposite ends thereof, the last-named section having a roller mounted thereon and carrying a screen fabric, strips secured to the side rails of the 45 roller carrying section and cooperating therewith to maintain the longer marginal edges of the screen slidably therebetween, grooved rollers in the openings of the said rails, and a cord connected to the outer end 50 of each of the rails of the first section extending through each of the openings thereof, around the grooved rollers and being connected to and wound on an end of the screen fabric roller. 55

In testimony whereof, I affix my signature, in the presence of two witnesses.

ALFRED W. EMERSON.

Witnesses:

OLIVE GASTON,
VIOLA LEIGHTON.
